UNITED STATES PATENT OFFICE.

MAX C. WALTER, OF CHAPPELL, NEBRASKA.

BASEBOARD AND SIDING GAUGE AND MARKER.

1,405,366.

Specification of Letters Patent. Patented Jan. 31, 1922.

Application filed October 29, 1920. Serial No. 420,470.

To all whom it may concern:

Be it known that I, MAX C. WALTER, a citizen of the United States, residing at Chappell, in the county of Deuel and State 5 of Nebraska, have invented certain new and useful Improvements in Baseboard and Siding Gauges and Markers; and I do hereby declare the following to be a full, clear, and exact description of the invention, such as 10 will enable others skilled in the art to which it appertains to make and use the same.

The object of the invention is to provide a simple and efficient means whereby base boards and siding boards may be readily 15 gaged or measured and fitted and marked to indicate where they should be cut or sawed transversely to fit or form proper joints with adjacent portions of the framing of a building or like structure, and particularly to provide a device which is adapted 20 for gauging and marking base boards, the location and position of which in fitting the same to the bases of door frames and the like rendering it difficult to mark them under such conditions as to insure a tight joint 25 between the extremity of the base board and the edge of the base of the frame, owing to the fact that when the base board is long enough to overlap the base of the frame it 30 is deflected outwardly from the plane which it will ultimately occupy and has its inner or rear surface too close to the wall to permit of the introduction of a marking device or means such as is ordinarily available to 35 the carpenter, and with this object in view the invention consists in a construction and combination of parts of which a preferred embodiment is shown in the drawings wherein,

40 Figure 1 is a view of a base board and siding gauge and marker applied in the operative position to a base board in the act of measuring and marking the same for subsequent cutting,

45 Figure 2 is a plan or end view of the same, Figure 3 is a transverse sectional view, Figure 4 is a side view partly broken away or in longitudinal section,

50 Figure 5 is a detail view of the device with the reversible member thereof released or disengaged and turned to an angle with relation to the board engaging member or hook,

55 Figure 6 is a detail view in perspective of the marking plunger detached,

Figure 7 is a similar view of the locking

device for securing the reversible member in its adjusted relation with the body member or hook.

The appliance embodies essentially the 60 body member or hook 10 and the reversible member 11, pivotally connected intermediate to the body member as by a bolt 12 to permit of reversing end for end the positions relatively of said members. The body 65 member is provided with a longitudinal slot 13 open at one end and having substantially parallel sides, adapting it to be fitted over the edge of a base or siding board such as indicated at 14 with one edge of the said 70 member in contact with the edge of a door frame such as indicated at 15, when it is desired to determine where to mark the base board transversely to serve as a guide in cutting the same to insure a tight fit between 75 the end of the base board and the side edge of the casing.

The reversible member of the appliance carries a bodily movable member 16 consisting of a hollow frame having opposite ears 80 17 and 18 slotted as at 19 for engagement with the extremities of guide screws or bolts 20 or the equivalent thereof engaged with the reversible member 11, a spring 21 being interposed between the parallel portions 22 85 and 23 of said member and the reversible member which form the relatively movable elements of a grip which may be conveniently grasped in the hand of the operator to the end that the bodily movable member 90 may be forced in opposition to the tension of said interposed spring toward the reversible member. Carried by and extending between the ears 18 at one side of the frame 16 is a marking blade 24 preferably having 95 a serrated or toothed edge as shown which when the plunger frame is moved inward by the compression of the grip members, said edge is caused to intersect or project into the slot in the main or body member of 100 the appliance to come in contact with the surface of the base or siding board with which said slot is engaged, to the end that said board will be marked transversely in a plane parallel with and in substantial coincidence with that surface of the body member adjacent to which the marking blade is located. 105

The main or body and reversible members of the device are held in their adjusted positions by their mutual engagement at corresponding ends by a clamping loop 25 which 110

may be pivoted upon the main or body member as shown in position for embracing the adjacent end of the reversible member, said clamp being of looped form so as to 5 adapt it to swing over the end of said reversible member, and carried by the clamp and movable therewith is a centering or adjusting blade 26 adapted to fit into registering kerfs 27 and 28 formed respectively in 10 the extremities of the said body or main and reversible members to accurately hold the same in their proper aligned relations. When the clamping member is disengaged from the extremity of the reversible member, the latter may be reversed to position 15 the marking blade at the opposite side of the tool, so that the latter may be used either right handed or left handed or to mark a board in either direction or which runs 20 either toward the right or toward the left to suit the convenience of the operator and the requirements of the structure in connection with which the tool is employed.

It will be noted that the tongue 10^a forming 25 the outer side of the main or body member, or the outer side or wall of the slot formed in said member is of a thickness adapting it to pass readily between a base board and the wall adjacent to which it is 30 arranged, even though the frame in connection with which the base board is to be fitted is of comparatively thin material, and said tongue is preferably reduced toward its extremity to facilitate such introduction.

35 What is claimed is:—

1. A marker having a marking body, marking means, means pivoted on the body to reversibly mount said marking means, and a single fastening device to secure the 40 body and second means in each position.

2. A base board or siding gauge having a slotted body or main member for engaging the board, and a reversible member mounted upon said body member and carrying a 45 marking blade for movement parallel with and adjacent to the side surface of said body member, said reversible member being pivotally mounted upon the body member, and a clamping loop for engaging corresponding 50 extremities of said body and reversible member.

3. A base board or siding gauge having a slotted body or main member for engaging the board, and a reversible member mounted upon said body member and carrying a 55 marking blade for movement parallel with and adjacent to the side surface of said body member, said reversible member being pivotally mounted upon the body member, and a clamping loop for engaging corresponding 60 extremities of said body and reversible member, said clamp carrying a positioning blade for engagement with registering kerfs in the extremities of said members.

4. A marker having a mounting member 65 provided with a handle, said handle having an opening therethrough, a marking device movable on said member, a spring between said handle and device to normally maintain the marking device retracted, and said device having an opening registering with said first named opening so that the operator's hand may be disposed simultaneously in both openings to grasp the marker and project the marking device to marking position. 70

5. A base board or siding gauge having a slotted body or main member for engaging the board, and a reversible member mounted upon said body member and carrying a 75 marking blade for movement parallel with and adjacent to the side surface of said body member, said marking blade being carried by a spring returned reciprocable follower mounted upon said reversible member.

6. A base board or siding gauge having a 80 slotted body or main member for engaging the board, and a reversible member mounted upon said body member and carrying a marking blade for movement parallel with and adjacent to the side surface of said body 85 member, said marking blade being carried by a spring returned reciprocable follower mounted upon said reversible member, and said follower frame and reversible member being provided with complementary grip portions. 90

In testimony whereof I affix my signature in presence of two witnesses.

MAX C. WALTER.
